UNITED STATES PATENT OFFICE.

DUNCAN KENNER, OF NEW ORLEANS, LOUISIANA, ASSIGNOR TO DRY HAND MOP COMPANY, OF NEW ORLEANS, LOUISIANA, A CORPORATION.

MOP HEAD.

1,427,478.

Specification of Letters Patent. Patented Aug. 29, 1922.

Application filed June 15, 1921. Serial No. 477,763.

To all whom it may concern:

Be it known that I, DUNCAN KENNER, a citizen of the United States, and a resident of New Orleans, in the parish of Orleans and State of Louisiana, have invented certain new and useful Improvements in Mop Heads, of which the following is a full and complete description.

This invention relates to mop-heads which 10 are intended to be mounted upon handles for the purpose of scrubbing or dusting floors and the like.

In my former Patent No. 1,279,355, Sept. 17, 1918, for a mop, Reissue No. 15,274, 15 dated January 24, 1922, there is shown a mop handle to one end of which is attached part of a mop-head, the latter being adapted to spread out fan-wise over the floor during operation, and to be drawn up over the mop 20 handle by means of a sleeve rotated around the handle in order that the mop might be properly wrung out. The present invention is an improvement upon the disclosure of the former patent to which reference is made 25 for the broad principle of operation.

In mops constructed according to the above patent, it has been found desirable to provide a mop-head which may be replaced or renewed after long continued service. 30 It has also been found expedient to provide for the ready disassembly of the mop parts. The present invention accomplishes the above purposes in a simple and effectual manner.

35 A further purpose of this invention is to fasten the lower portion of the mop-head to the handle in such manner as to prevent circumferential slippage of the mop-head during the twisting action when the mop is 40 wrung out.

Other advantageous results arising from my invention will appear from the following specification of the invention as described hereinafter and illustrated in the accompanying drawings in which,

Fig. 1 is a side view of the mop-head partly in section.

Fig. 2 is a side view of the mop and mop head during the wringing operation, and

50 Fig. 3 is a perspective view of the ferrule.

One form of my invention is illustrated in the drawings in which the mop handle 5 has a reduced end 6. A loose spiral 7 of resilient material preferably metal is carried upon the reduced portion 6 of the

handle. This spiral member 7 rests loosely against shoulder 8 of the handle. The diameter of the spiral is slightly in excess of the corresponding diameter of the handle. A hollow sleeve 9 forming a hand grip is 60 slidably carried upon the handle over the spiral 7.

A ferrule 10 made of brass or analogous material is provided having an internal diameter slightly greater than the diameter 65 of the handle portion 6. The ferrule has one or more ribs 11, 11, extending outwardly in an axial direction from the surface of the ferrule. It is preferred that these ribs be interrupted to provide openings indicated at 70 12 in Fig. 3. The ribs 11, 11, begin at one end of the cylindrical ferrule and may extend substantially the length of the latter. A hole 13 is drilled through the ferrule at a convenient point. 75

A covering 14 made of textile material is provided as the absorbent part of the mop-head. This member 14 may be made of strands of yarn, knitted or woven fabric, or other analogous material. If made of 80 loose strands of yarn as illustrated in the drawings, the strands 15 are disposed in two layers, the ends being suitably attached to the hand grip 9 by means of circumferential fastenings 16. These fastenings 85 may be of yarn or wire and may be adapted for ready removal. The strands of yarn are looped as at 17 and bound together by a ring or fastening 18. Suitably spaced along the lengths of the strands are cross stitchings 19 and 20 which serve to maintain the strands in fixed relationship one with another but capable of limited spreading movement away from the axis of the handle. The looped portions 17 are brought back over the 90 sides of the ferrule and bound thereto by means of the ring, wire or other binding 21. This member 21 falls within the opening 12 of the rib 11, 11.

The mop-head is ordinarily assembled independently of the handle and helix 7. To apply the complete mop-head to the handle it is only necessary to constrict the spring member 7 and permit the ferrule 10 to be passed over the end of the handle member 6. 100 A screw 22 passed through the hole 13 of the ferrule will hold the latter firmly on the handle. The released spring 7 will then abut against the end of the ferrule. 105

It will be apparent that when the sleeve 110

or hand grip 9 rests in proximity to the ferrule the covering is practically doubled and spreads out over the surface which is being treated. The looped portions 17 act as a sheath to prevent the metal ferrule from coming in contact with the floor or furniture. To wring out the covering the sleeve 9 is drawn up and twisted relatively to the handle 5 as shown in Fig. 2. Due to the 10 excess in diameter of the spring 7 the latter is constricted when the covering is wrung out and when the latter is released it will be lifted from the handle 6 by the expansion of the spring 7. Likewise, the spring 15 7 is capable of lateral torsion to accommodate the movement of the strands of the covering during twisting.

After long continued use the binding 21 may become somewhat slack but the covering 20 will be held from slipping by means of the ribs 11, 11. When it is desired to renew the mop-head an opening is made in the covering and the screw 22 removed. The ferrule, together with the covering and 25 sleeve 9 is then slipped off. A new mop-head may then be inserted in the manner indicated.

While I have described one preferred form of my invention it will be evident that 30 various changes in material, proportion, and details may be made without departing from the spirit of my invention as herein claimed.

What I claim is:

35 1. In a mop-head, a hollow cylindrical

ferrule, longitudinal ribs thereon and a stranded textile covering surrounding one end of the ferrule and fastened thereto with the strands parallel to said ribs.

2. In a mop-head a ferrule adapted for 40 removable attachment to a handle, a covering of textile material covering the end of the ferrule, means to fasten the covering around the ferrule, and a sleeve to which a part of the covering is fastened. 45

3. In a mop-head a ferrule adapted for removable attachment to a handle, a covering of textile material surrounding the end of the ferrule, means to fasten the covering around the ferrule, means on the ferrule preventing the circumferential slippage 50 of the covering, and a sleeve to which a part of the covering is fastened.

4. In a mop-head, a ferrule, means for removably attaching the ferrule to a handle, 55 a covering of textile material fastened to the ferrule, a rib on the ferrule to prevent circumferential slippage of the covering and a sleeve to which a portion of the covering is fastened. 60

5. In a mop-head, a ferrule, means for removably attaching the ferrule to a handle, a covering of textile material fastened to the ferrule, an interrupted rib on the ferrule to prevent slippage of the covering and 65 a sleeve to which a portion of the covering is fastened.

In testimony whereof I hereunto affix my signature.

DUNCAN KENNER.
